1

The invention relates to automatic or semi-automatic telephone and similar systems, in which one or more group selector stages are used.

In telephone or similar systems (so-called "telecommunication systems") automatic switching systems or stages are employed comprising group selectors and final selectors, which are operable to select a free outlet in a predetermined group, or (in a final selector) a particular predetermined outlet.

This invention deals particularly with methods of operating stages of group selectors in such systems. Two distinct functions are performed in a group selecting stage, viz. the selection of a particular group of outlets, and the hunting for a free outlet in the selected group of outlets. The selecting action is controlled either directly or indirectly by the calling subscriber, who must in some way or another indicate the destination of the connection. The hunting action takes place automatically, independently of the calling subscriber, and is performed by the automatic group selector stage or equipment itself.

Group selectors of different types may be divided into forward or directive impulse types which have a step-by-step movement, and reverte

re impulse types in which driving power is obtained from a common motor.

Group selectors are known in which power may be applied either from a common motor or from a source individual to the selector and which are not controlled by directive or reverte but by marking impulses. In such systems forward or reverte impulses are used to set a separate marker switch, which may be either individual to a selector or common to a plurality of selectors, and which connects a marking potential to the so-called marking level of the selector bank.

Step-by-step switches are usually provided with a selector bank of ten levels, each containing a certain number of sets of bank contacts, each serving an individual outlet. The selecting movement in this case is used to bring the wipers of the brush carriage to a particular level, and the hunting movement is made by letting these wipers pass over the different sets of bank contacts of the selected level. The number of accessible outlets is limited to the number available in each level. This number is invariable, because it is determined by the construction of the switch.

The reverte impulse type of selector switch is usually controlled by a register controller and has bank contacts containing a larger number of outlets in each level than the directly controlled

2

switch, because the register controller allows for hunting over a period independent of the speed of sending the numerical indications denoting the destination of the connection. In principle, however, the arrangement of the selector bank has the above mentioned limitations because the number of outlets in each level is limited by the construction of the switch. This may in a good many cases lead to an uneconomical employment of the selector switch.

The marker type of switch has usually a single motion and its bank contacts are arranged in one row which is wiped over by a single set of brushes. The bank contacts may be arranged in two rows, which are wiped over by two sets of brushes staggered 180°. Other arrangements are also known which insure that all sets of contacts in the bank will be reached during one cyclic operation of the brush carriage.

20 In such switches the sets of bank contacts are subdivided into any number of groups, as dictated by the switching requirements, and each group may contain any number of outlets. The only limitation is that the sum of the outlets for each group do not exceed the total number of sets of bank contacts provided in the bank.

One disadvantage of all single motion switches is that it cannot be used alone, but must always have some helping mechanism, viz. a marker switch. This circumstance more or less outweighs the advantage of the single motion switch over the two-motion switch. Moreover, marker systems require, in some cases, the provision of complicated common control circuits. In the absence of a common control circuit one marker switch per selector would have to be provided. Since the marker switch is used only during the setting of the selector onto a free outlet in the wanted group, it is not used most of the time

40 when provided individually per selector. On the other hand, if a control circuit is provided, then upon its use for one of the selectors all other selectors become temporarily disabled and must wait for the control circuit to become free. Furthermore, the common control circuit constitutes a vulnerable point in the switching system and damage to it endangers the whole system.

50 The present invention relates to a switching system using single motion switches requiring no control circuits and no marker switches. The selecting and hunting operations are controlled by a common register controller which serves all of the switching stages without the interposition of any marking system or similar expedients. Whenever in prior systems single motion

switches were employed without markers, either associated with the selector or in a common control circuit, marking connections were provided to the marking level of the selector directly from a register controller. Such systems have been employed only on a limited scale and in a limited number of selector stages, because the marking multiple must be either common to all register controllers, in which case only one selection can be made at a time in each selecting stage, or it must be divided into a number of splits which are connected by means of some connecting arrangement to a particular register controller, but only when required, in which case these connecting arrangements are the source of considerable complication and confusion, besides being expensive.

In the system embodying the various features of the present invention there is no limitation as to the number of connections that may be handled simultaneously, and there are no such complications as the provision of a connection from the marking level to the register controller handling the connection.

One possible method of effecting direct control of selecting and hunting from common register controllers is to do this by means of retractive impulsing, i. e. by sending a make impulse or a break impulse in a closed circuit from a moving selector to the register controller, either when each group of outlets is reached or when each individual bank contact is engaged by the wipers of the selector.

When considering the sending of an impulse for every group, it should be borne in mind that the manner in which the groups can be divided in the bank is rather restricted. This is so because it is desirable to keep this division as simple as possible, and thus not to complicate the arrangement at the register controller where a switch must be provided having wipers advancing one step for each retractive impulse received from the selector under control for the purpose of permitting the selector to test only one group of outlets in a particular predetermined position.

If the outlets of one level were divided at random over the whole bank, the switch at the register controller would have many positions in which it permits the selector to test, and still many more positions in which it does not permit the selector to test. A retractive impulse would have to be sent each time the selector wipers reach outlets belonging to a different group. Changes in the arrangement of the group selector outlets would then be reflected in a changed arrangement at the register controllers, etc.

The sending of a retractive impulse for each bank contact passed over by a selector wiper is one way of doing this, though in an extreme case the switch at the register may have to be provided with as many positions as there are sets of bank contacts in the selector.

Both arrangements have the general disadvantage that they require at the controller a moving switch capable of following fast and accurately the impulses received from the selector.

According to the present invention single motion switches are directly controlled from register controllers without using retractive impulses and without the necessity of providing movable apparatus at the register controller.

We employ the signaling system described in the co-pending application Serial No. 472,623, filed January 16, 1943, by Simon et al., now Patent No. 2,424,585, dated July 29, 1947, in which

use is made of a plurality of sources of current to differentiate between the different groups of outlets in the selector bank.

When the selector brushes move over the bank contacts of a particular outlet, a signal is transmitted from the selector to the register controller for each outlet passed over by the brushes. This signal is characteristic for the particular group and will inform the register of the fact that the selector engages a set of bank contacts of the group of outlets to be selected.

No distinct selecting and hunting operations are performed and the selector moves under the control of the register controller until its wipers find an outlet having on its test terminal the particular signaling current to which the register controller is set to respond. One of the advantages of this scheme is that the selector circuit is extremely simple, only two relays being required to control the single motion selector which itself is of very simple design, since it performs only a single movement. Furthermore, the speed of operation may be extremely high. The absence of directive or retractive impulses is also an advantage as is the absence of mechanism for counting these impulses at the selector or in association with the selector and at the register controller. Moreover, the arrangement of the outlets in the selector bank is flexible, because the outlets may be arranged in any conceivable manner, without requiring a corresponding adaptation at the register controller. Due to the absence of a marking multiple, the number of simultaneous selections is not limited, and no such artificial load is placed on the selectors as is the case when a common control circuit is taken into use for one of the selectors of the group served. The system has no such vulnerable part as a common control circuit. The wiring of the selector banks is extremely simple, because there are no marking levels which have to be split according to the size of the group to be served by one control circuit or to be served by one set of connecting apparatus establishing a connection with the register controllers.

Description of the circuit operation

The invention will now be described with the aid of the drawings in which so much of a telephone exchange as is necessary to understand the invention is diagrammatically illustrated. Figs. 1, 2 and 3 should be placed one below the other. They represent a register controller, but illustrate only those parts thereof which are required for the understanding of the selecting operation. Fig. 4 illustrates a group selector and should be placed to the right of Fig. 1. Fig. 5 is an alternative for Fig. 4.

It is assumed that a subscriber's call is picked up by line finders in the known way and that a register circuit is attached to the calling line over a suitable link circuit. The group selectors of the different stages have all the same circuit as shown in Fig. 4, with the exception of a slight modification in the wiring, so that the wires marked *x* may be left out in the first group selector. It is assumed that the first group selector is permanently connected to the customary second line finder circuit and is, therefore, engaged without preceding selection. The second and third group selectors are identical. Figs. 1, 2 and 3 control three selections, viz. those performed by the first, second and third group selectors, whereupon the final selector is reached.

(a) Reception of digits

The digits of the called subscriber's number to which the connection has to be extended, are sent by the calling subscriber in form of dial impulses, in the known way. Relay I_{sr} is operated when the call is originated and releases for each opening of the dial contact.

When operating the first time relay I_{sr} energizes the relays L_{br} and L_{hr} . Relay L_{br} is a slow releasing relay and remains operated during dial impulsion.

The first digit is stored on the step-by-step switch SM_1 . On the first opening of the dial contacts magnet SM_1 is energized over the circuit: ground, I_{sr} back, L_{br} front, winding L_{mr} , D_{r1} back, magnet SM_1 , battery.

Relay L_{mr} operates on the first impulse and remains energized during the train of impulses of one digit. Switch SM_1 advances by one step each time relay I_{sr} releases and stops finally in a position corresponding to the number sent by the subscriber.

Relay I_{sr} remains during the interdigital time on its front for a time sufficient to release relay L_{mr} . The switch magnet IM was kept operated by relay L_{mr} during the reception of the digit, becomes de-energized and moves its brushes (Fig. 2) into position 1 whereupon relay D_{r1} operates. Relay D_{r1} changes over the stepping circuit from switch SM_1 to SM_2 over a front contact of D_{r1} and a back contact of D_{r2} so that the second digit will be received by switch SM_2 in the same way as the first digit was received by SM_1 . The magnet of switch IM is again kept energized during the reception of the dial impulses upon the termination of which relay D_{r2} operates. The third digit will be directed to switch SM_3 . Upon the reception of the third digit relay D_{r3} is energized. The reception of further digits is not shown in the drawing.

Relay Chr (Fig. 2) is controlled at the front of relay I_{sr} and it therefore follows the impulses of the first digit. The circuit extends: ground I_{sr} front, F_{tr} back, V_{tr} back, Chr , battery. The purpose of this relay will appear from the description below.

(b) Alternating current testing

As soon as the first impulse of the first digit has been registered by switch SM_1 , the first group selector switch starts to rotate in hunt for a free second group selector in the group indicated by switch SM_1 . For the sake of simplicity we will first consider one hundred point selector switches with ten groups of outlets, each group having ten such outlets. The selector switch has its normal position in front of the group corresponding to the number "0." The next group, corresponding to the number "1" starts ten terminals further, the group for number "2" again ten terminals further, etc. Assuming that the dial impulses are received faster than the advance of the brushes of the selector switch over the different groups, when the brushes of switch SM_1 (shown below the magnet in Fig. 3) come to rest on the terminal corresponding to the digit sent, the brushes of the selector will not yet have reached the first outlet of the corresponding group. It will be explained later under the heading "Speed-up" that the circuit operation is correct under all switching conditions with different time limit.

As soon as the register is engaged, relay Ar (Fig. 4) operates over the circuit: ground, brush and normal terminal "a" of switch SM_1 , L_{hr} front,

"b" wire, Br back, Ar back, Ar , battery. Ar locks itself over the "d" wire to the front of L_{hr} .

The power magnet P of the selector switch is now energized and the brush carriage starts to rotate in the circuit over: ground, brush and first terminal "a" of switch SM_1 , terminal "N" and brush "c" of switch OM , V_{tr} back, F_{tr} back, V_{rr} back, "a" wire, Br back, Ar front, magnet P , battery.

10 The selection is determined by comparing the alternating current signal received from the group selector with the alternating current signal available over the arcs "b" of switches SM_{1-3} . These two currents are compared in the register controller. The comparing equipment is shown in Fig. 2 and includes transformers HC_1 , HC_2 , VT , tubes T_1 , T_2 and relay V_{tr} .

The operation of this equipment has been described in full detail in the above mentioned application. The signaling current is the alternating current received from the selector circuit and the reference current is the alternating current connected over the arcs of switches SM_{1-3} .

25 The circuit of the signaling current can be traced as follows: The source of alternating current S , resistance R_1 of 100ω , home contact of the selector, busy jack BJ , Ar back in the second group selector, "d" brush of the first group selector switch (Fig. 4) and Br back, Ar front, of the preceding selector, "c" wire, Str back and primary winding of HC_1 .

30 The circuit for the reference current is as follows: The alternating current source $Ref.$ (Fig. 3) resistance of 100ω , terminal "b" of switch SM_1 to which it was set, normal terminal and brush "d" of switch OM , and the primary winding of transformer HC_2 .

35 When equipment detects that the signaling and the reference currents are in phase, then the cold cathode tube T_2 becomes ionized, relay V_{tr} operates and consequently the selector stops on the terminals of an outlet in the wanted group.

40 Upon the energizing of relay V_{tr} , relay F_{tr} is energized over the circuit: ground, brush "a" and terminal "1" of arc of switch SM_1 , terminal "N" and brush "c" of switch OM , V_{tr} front, F_{hr} back, winding of relay F_{tr} , battery.

45 Relay F_{tr} prepares a locking circuit for itself over the winding of F_{hr} and opens the circuit of Chr . Chr removes the 130 volt positive battery from the anode of the tube T_2 . V_{tr} releases and removes the short-circuiting ground from relay F_{hr} and this relay operates in series with relay F_{tr} via back of V_{rr} and front of relay L_{hr} . Relay F_{hr} again closes the operating circuit of relay Chr , which operates so that the tube T_2 lights again, the alternating current signal from the selector being still sent. Relay V_{tr} operates again and closes the following circuit for relay Str : ground on the armature of V_{tr} , F_{hr} front, winding of relay Str , battery.

50 The operation of relay Str signifies that the alternating current test is completed and the register may proceed with the direct current test.

55 The alternating current test is made twice in order to make sure that the selector switch is standing on the terminals of the outlet on which it was stopped.

(c) Direct current testing

75 Relay Str closes the following direct current test circuit: ground, Str front, 2000ω winding of Tr , G_{br} back, wire "b," Br back, Ar front, winding "I" of relay Br , brush "c" of first group selec-

tor, Ar back, resistance R_2 of 600ω , battery in the second group selector.

In this circuit relay Tr alone can operate and relay Br , due to the high resistance of relay Tr , does not operate. The front of Tr connects relay Dtr and its low resistance winding in parallel to its own high resistance winding making the test potential of 600ω busy against other calls and increasing at the same time the current so that Br can operate. Relay Dtr is a marginal relay and can only operate if it alone is connected to the test potential. Upon the energizing of relay Dtr relay Sar is energized. Relay Sar energizes the step-by-step switch OM as well as the relay Vrr .

Relay Vrr opens the locking circuit of Fhr and Ftr which release together with relay Str . The test relays, however, remain operated due to the second ground connected to the front of Tr via a front of Sar . Relay Vrr releases relay Chr so that the tube T_2 becomes extinguished and relay Vtr releases.

After being energized relay Sar locks itself to the interrupter contact of switch OM to make such that switch OM is fully energized. When the first group selector is connected-through by the operated relay Br and the seizure relay Ar in the second group selector is energized, the 600ω test potential R_2 is disconnected. This part of the circuit operation will be given in detail below.

In the register controller relay Dtr releases when the test potential is removed and, if switch OM at this moment is already fully energized, relay Sar releases. The brushes of switch OM now make one step and arrive at terminal 1.

Relay Sar releases relay Vrr and this in turn allows the reoperation of relay Chr , so that now the receiving equipment is ready for the next test.

The ground of the low resistance circuit of relay Tr and relay Dtr is controlled over different contacts. Details of this circuit will be given under "Speed-up."

(d) *Group selector connected through*

Relay Br in the first group selector starts to operate as soon as the high resistance winding of relay Tr is shunted by relay Dtr . Relay Br is slightly slow to operate due to its short-circuited second winding thus to cover the releasing time of the test relays in case of simultaneous tests by two or more circuits.

As soon as relay Br operates, it removes the short-circuit from its winding II and provides a locking circuit to the battery over resistance R_2 . In addition, it short-circuits its operating winding I via a front contact which closes later than the short-circuiting back contact.

The signaling current still available from the second group selector over brush "d" of the first group selector is rendered busy by a full ground connected over a front of relay Br . The left-hand side contacts of Br connect through the "b" and "c" wires in such a way that the test potential of the second group selector over the brush "c" is continually guarded.

When relay Str operates after successful alternating current testing, it disconnects the primary winding of transformer HC_1 and replaces it by a second low resistance winding of relay Dtr . When relay Br energizes, it connects this second winding of relay Dtr over its left outer change-over contact to the "c" wire in parallel with the other winding I of relay Dtr . The inner change-over contact at the left-hand side con-

ncts through the "b" wire towards the second group selector. At this moment the test potential is guarded by the second winding II of relay Dtr .

At the moment the "b" wire is connected through the low resistance circuit including relay Tr and relay Dtr energizes relay Ar of the second group selector in the following circuit: ground, Sar front, primary winding I of relay Dtr , Tr , Gbr back, "b"-wire, Br front and brush "b" of first group selector, and in the second group selector, Br back, Ar back, Ar , battery.

Relay Ar operates in this circuit and locks itself over brush "d" to the ground available via front of relay Br in the first group selector. The alternating current which was already short-circuited by the above mentioned ground is now disconnected at the back of relay Ar in the second group selector. Relay Ar disconnects also the direct current test potential of 600ω , whereupon relay Dtr becomes de-energized as above described.

(e) *Failure of the alternating current test*

The alternating current test is repeated in order to make sure that the group selector after stopping engages the terminal "d" of the group selector of the next stage. Should it happen that the brushes of the selector move too far so that the circuit over brush "d" is opened, then the following changes take place:

30 On the first operation of relay Vtr , relays Ftr and Fhr also operate as above described. Relay Chr connects the positive battery to the tube T_2 , but the tube does not operate and relay Vtr remains deenergized. Relay Kir energizes in the circuit: ground on the armature of relay Vtr , Vtr back, Ftr front, Fhr front, relay Kir , battery.

35 Relay Kir energizes relay Vrr , which releases relays Ftr and Fhr . Relay Kir releases as soon as relay Fhr opens its front contacts so that Vrr upon releasing re-establishes the alternating current test conditions as before. The power magnet of the group selector is energized again and the brush carriage continues to hunt for another free outlet in the wanted group.

45 (f) *Failure of direct current test*

The direct current test may fail if the stopping of the selector switch is delayed, so that the circuit over brush "c" is opened, or in case the test potential is kept busy by another circuit which has just performed the same alternating current test, or because the fuse of the outlet engaged is out.

In all these cases relay Tr does not operate and the relay Gbr is energized.

50 Relay Gbr disconnects the test relay Tr and connects the "b" wire to the control cathode of the cold cathode tube T_3 . At the same time this relay energizes the power magnet of the selector switch over the "a" wire. The brush carriage leaves the position in which the direct current test was not successful and will advance until it reaches the first free test potential of any free outlet.

65 The control cathode of tube T_3 is permanently connected to a positive battery of about 30 v. The control anode is connected to ground. The tube therefore will not light on busied test potential, because the 30 v. is not sufficient to break down the discharge space. As soon as a free potential of 48 v. is found, the potential difference increases to 78 v. and the tube becomes ionized. Relay Fsr operates and stops the selector on the terminals of a free outlet which, of course, does not necessarily belong to the same group as the

outlet tested before. Relay *Fsr* energizes *Vrr*, which causes the release of relays *Fhr*, *Ftr*, *Str* as well as *Chr* and *Vtr*.

The release of relay *Str* is followed by that of relay *Gbr*, whereupon the tube *T*₃ is extinguished and relay *Fsr* releases. The circuit is now ready to start again the alternating current test. If, therefore, the group selector does not reach the contacts of the group designated by the reference current, then the selector switches will have to start again to rotate.

(g) *Speed-up*

The speed-up arrangement has for its purpose to speed up the selection and it consists in that the rotation of the selector brushes takes place simultaneously with the reception of the numerical indication designating the group of outlets, a free one of which must be selected.

The first requirement is that the outlets of the switching stages be connected to the banks of the preceding selector switches in the same order as the numbering of the dial by means of which the subscriber send the digits. The second requirement is that the time required by the selector brushes to wipe over the terminals of any of the outlets should be greater, or at least equal to the time taken by one dial impulse. It is further necessary to provide the group selector with a home position from which its brushes start their hunting operation.

The second requirement concerns the speed at which the selector brushes have to rotate. This speed will depend on the number of outlets in the different groups. Large groups can be split into several smaller groups and spread over the whole arc in any convenient way, but the section which is first encountered by the rotating brushes of the selector must be large enough to require a rotating time at least equal to one dial impulse.

The home position of the selector brushes is fixed in such a way that normally the brush carriage is one outlet behind the position of the step-by-step switch *SM*. If, therefore, the selector reaches the first outlet of a group, the switch *SM* will already connect the reference current of the following group and the selector brushes will not stop. If, however, the brushes of the switch *SM* have been already set into the required position, the selector brushes will stop on the first free outlet because the signaling current received through this outlet will be identical with the reference current. However, the idle outlet thus found cannot be definitely engaged until the release of the slow relay *Lmr* indicates with certainty that no more impulses will be sent, i. e. that the digit received is complete.

The dial speed may be variable (8-14 steps per sec.) and it may happen that in case of a very slow dial the selector reaches a free outlet in a group whilst this is still indicated by the position of switch *SM*. The tube *T*₂ operates in this case and the selector brushes stop. If now a further impulse is received, then the tube *T*₂ has to be extinguished and the selector brushes have to rotate again. It may also happen that in the case just mentioned, all outlets of the group are occupied and therefore the selector brushes cannot stop, but go over to the outlets of the next group. As a consequence of this the selector brushes may advance too far, beyond the group indicated by *SM*. The selection, however, will be correct under all circumstances because the selector brushes can only stop in response to the predetermined signaling current. The selector brushes must, there-

fore, continue their rotation until they find a free outlet in the desired group.

The above requirements are satisfied by the following circuit arrangements:

5 The brushes of the first group selector switch start to rotate when the brushes of switch *SM*₁ are advanced by the first impulse to terminal *t*. Relay *Chr* follows the impulses and on each opening it removes the 130 v. battery from the anode 10 of tube *T*₂. As soon as the digit is complete relay *Chr* remains energized, whilst relay *Lmr* releases and the brushes of switch *IM* take one step. Relay *Dir*₁ operates and provides a holding ground for *Chr* via arc "a" of switch *OM*. Relay *Chr* remains 15 operated until the selection is terminated and is released by relay *Vrr*.

Should the brushes of the group selector, on account of low dial speed, stop on the terminal of an outlet which is not the wanted one, then relay 20 *Chr* releases when the next impulse is received and extinguishes the tube *T*₂, releasing thereby relay *Vtr* and forcing the group selector to leave its position. When relay *Chr* re-operates, the brushes of the switch *SM*₁ will already be in the 25 next position and connect another reference current.

If the first selection is terminated before the second digit is sent, or whilst it is being sent, then relay *Chr* follows again the impulses, acting on 30 relay *Isr*, and the speed-up takes place in the second group selector.

An outlet tested by alternating current can be definitely engaged only when relay *Lmr* is released. When the alternating current test is 35 completed and relay *Str* operates, only the high resistance winding of *Tr* is connected towards the test potential, and no circuit will be found for the low resistance winding of relay *Tr* and, therefore, for relay *Dtr*. This circuit will be closed as soon 40 as relay *Lmr* releases. On the other hand, if the digit has already been received when the alternating current test takes place, then the outlet will be immediately engaged by the complete direct current test, ground being provided via 45 front of relay *Dir* and arc "b" of switch *OM* independently of the back of relay *Lmr*, which may already be open due to the reception of the next digit.

(h) *Circuit variants*

The above disclosed circuits and operations have been described by way of example only. It is evident that obviously, the invention is in no way limited to the specific arrangements described, 55 and many alternatives are possible.

For example, in the circuits described the selector switches have a home position to which they are returned upon the termination of each call, a switch becoming available for the next call only 60 when the home position is reached. This may be varied so that no home position is provided, in which case the home contact, certain relay contacts and wiring connections, which are required for controlling the return to the normal position 65 may be omitted. In this case it may be preferred to omit the speed-up feature which permits a group selector to commence moving while the numerical indication is being received at the register controller, and instead to commence the selecting and hunting action only when the numerical indication has been completely received.

The group selector switch may be of a variety of designs. The example disclosed herein is a single-motion switch with common motor drive,

11

but switches with individual step-by-step movement or having individual motors or of any other design may be used.

In the example given the characteristic potential is opened at a relay contact of the selector circuit immediately after seizure by a preceding selector. This is not essential for the operation of the system and is suggested only in order to permit the brush of a hunting selector switch to pass a busy terminal without stopping momentarily. By omitting this contact the selecting and hunting actions would be segregated, because the brushes of the switch would in one continuous movement go to the first outlet of a group and subsequently commence a step-by-step movement from one terminal to the next until a free outlet is found, each terminal being tested for free or busy condition while the switch stopped on it.

The arrangement of the two relays in the circuit can also be varied. The circuit may, e. g., be designed so that the seizure relay is released by the operation of the switch-through relay, and the latter being made to hold onto the preceding selector, or independent of the former relay. Another possibility is so to design the circuit that the seizure relay is operated as long as the circuit is engaged for a connection, but that the second relay, denoted as the switch-through relay, is so connected that it operates during the selection and hunting action only. This leads to still another possibility, viz. to combine the functions of the power magnet of the switch with that of the last-mentioned relay by placing the relevant contact springs on the magnet assembly so that they are operated only when the switch magnet is energized. In this way the second relay coil and armature may be omitted. A circuit of this kind, which therefore has one relay only, is shown by way of example in Fig. 5. In this figure the brushes *a*, *b*, *c*, *d* are on terminals of the home position. The armatures *p*₁, *p*₂, *p*₃ and *p*₄ are operated by the selector magnet.

What is claimed is:

1. In a telecommunication system, a plurality of numerically designated lines, selector switches for connecting a calling line towards a called line, said selectors having cyclically operated movable contacts and cooperating sets of stationary bank contacts over all of which said movable contacts move consecutively during each cycle, electromagnetic means for controlling the movement of said movable contacts, groups of outlets connected in multiple to the bank contacts of all selectors, a register controller, means for temporarily associating said register controller with a selector, means associated with the calling line for operating said controller to register the numerical designation of the called line, a control circuit extending from the register controller to the connected selector for controlling said movable contacts to select a group of outlets determined by the numerical designation of the called line and to hunt for an idle outlet in the selected group, means in the connected selector for applying a signaling potential to the control circuit which is characteristic for an outlet with which the movable contacts are connected, there being a plurality of different sources of potential, each characteristic for a different outlet, and a responsive device for controlling the operation of the controller actuated by the signaling potential.

2. The arrangement of claim 1, characterized in that each group of outlets is identified by a characteristic source of potential applied to a bank contact.

12

3. The arrangement of claim 1, characterized in that each group of outlets is identified by a characteristic source of alternating current potential applied to a bank contact.

4. The arrangement according to claim 1, characterized in that an outlet seized by the movable contacts of a selector is made busy in the bank contacts of all the other selectors, and means for applying the characteristic signaling potential only to the bank contacts of idle outlets.

5. The arrangement according to claim 1, characterized by means jointly controlled by the controller and the selector connected therewith for simultaneously performing the selecting and hunting operations thereof.

6. The arrangement of claim 1, characterized in that signal receiving equipment at the register controller is set under the control of the numerical designation of the called line, said arrangement further including a circuit for the electromagnetic means of the connected selector extending to said controller, means in the controller for closing said circuit upon the beginning of the operation of the controller in accordance with the designation of the called line, and means in the controller for opening the last mentioned circuit upon the completion of the hunting movement of the selector contacts.

7. The arrangement of claim 1, characterized by test means in the register controller, a circuit for said test means closed upon the stopping of the contacts of the connected selector switch, a source of direct current potential applied to the last mentioned circuit at the selector, and a circuit for the electromagnetic means controlled by said test means.

8. The arrangement of claim 1, characterized by a switch-through relay at the selector switch, means controlled by the register controller for operating said switch-through relay upon the completion of the hunting, a conversational condition established through said selector upon the operation of said relay, and means for rendering the characteristic potential of an outlet ineffective for selecting and hunting selector switches controlled by said relay.

9. The arrangement of claim 1, characterized by a switch-through relay at each selector for completing the connection through an outlet, a test relay at the register controller, a circuit for the electromagnetic means for said selectors controlled by said test relay, and a potential of direct current provided at each outlet for operating said switch-through and test relays.

10. The arrangement of claim 1, characterized by a switch-through relay at each selector for completing the connection through an outlet, a test relay at the register controller, a circuit for the electromagnetic means for said selectors controlled by said test relay, and a potential of direct current provided at each outlet for operating said switch-through and test relays, and a locking circuit for the switch-through relay independent of the register controller and the direct current potential at the engaged outlet.

11. In a telecommunication system, a plurality of numerically designated lines, selector switches arranged in successive stages for connecting a calling line towards a called line, said selectors having cyclically operated movable contacts and cooperating sets of stationary bank contacts over all of which said movable contacts move consecutively during each cycle, electromagnetic means for controlling the movement of said movable contacts, groups of outlets connected in multiple to the bank contacts of all selectors, a register controller, means for temporarily associating said register controller with a selector, means associated with the calling line for operating said controller to register the numerical designation of the called line, a control circuit extending from the register controller to the connected selector for controlling said movable contacts to select a group of outlets determined by the numerical designation of the called line and to hunt for an idle outlet in the selected group, means in the connected selector for applying a signaling potential to the control circuit which is characteristic for an outlet with which the movable contacts are connected, there being a plurality of different sources of potential, each characteristic for a different outlet, and a responsive device for controlling the operation of the controller actuated by the signaling potential.

the bank contacts of all selectors of a stage, a register controller, means for temporarily associating said register controller with selectors of successive stages, a seizure relay at each selector operated upon its connection with the controller, a locking circuit for the relay independent of the controller, means associated with the calling line for operating said controller to register the numerical designation of the called line, a control circuit extending from the register controller to the connected selector for controlling its movable contacts to select a group of outlets determined by the numerical designation of the called line and to hunt for an idle outlet in the selected group, means in the connected selector for applying a signaling potential to the control circuit which is characteristic for an outlet with which the movable contacts are connected, there being a plurality of different sources of potential, each characteristic for a different outlet, a busy test potential applied to the multiples of an engaged outlet under the control of said relay, means for disconnecting the characteristic signaling potential applied at a selector of one stage controlled by the relay of the selector of the succeeding stage, and a responsive device for controlling the operation of the register controller actuated by the signaling potential.

12. In a telecommunication system, a plurality of numerically designated lines, selector switches for connecting a calling line towards a called line, said selectors having cyclically operated movable contacts and cooperating sets of stationary bank contacts over all of which said movable contacts move consecutively during each cycle, electromagnetic means for controlling the movement of said movable contacts, groups of outlets connected in multiple to the bank contacts of all selectors, a register controller, means for temporarily associating said register controller with a selector, means associated with the calling line for operating said controller to register the numerical designation of the called line, a control circuit extending from the register controller to the connected selector for controlling said movable contacts to select a group of outlets determined by the numerical designation of the called line and to hunt for an idle outlet in said group, means in the connected selector for applying a signaling potential to the control circuit which is characteristic of an outlet with which the movable contacts are con-

nected, there being a plurality of different sources of potential, each characteristic for a different outlet, a responsive device for controlling the operation of the controller actuated by the signaling potential, means for applying a source of test potential to the multiples of an outlet, a test relay in the controller actuated from said source of test potential, and an energizing circuit for the electromagnetic means controlled by said test relay.

13. The arrangement of claim 1, characterized in that the movable contacts of each selector are brushes, one of which engages its cooperating bank contact later than the other brushes when moving towards a set of contacts and opens earlier than the other brushes when leaving a set of contacts, said arrangement further including test relays at the register controller operable upon the engagement by the selector brushes on the contacts of a wanted outlet, a source of test potential connected to the contact bank of a selector, and circuits for operating said test relays from said sources of characteristic potential and test potential.

14. The arrangement of claim 1, characterized in that the movable selector contacts have a normal position, and means for moving them into the normal position after the completion of a connection.

15. The arrangement of claim 1, characterized in that each selector switch is provided with two relays only for controlling all said operations.

16. The arrangement of claim 1, characterized in that the electromagnetic means of a selector is a magnet having contact springs, and a relay having contact springs associated with each selector, all the circuits of a selector being controlled only over the contacts thereof and the contact springs of the associated magnet and relay.
